US0D1022362S

(12) **United States Design Patent** (10) Patent No.: **US D1,022,362 S**
(45) Date of Patent: ** Apr. 9, 2024

(54) **SWIMMING POOL CLEANER WITH
CONTROLLER**

(71) Applicant: **Degrii Co., Ltd.**, Jiangsu (CN)
(72) Inventors: **Dongsheng Liu**, Jiangsu (CN); **Tao Zhu**, Jiangsu (CN); **Liang Zhong**, Jiangsu (CN); **Ye Zhao**, Jiangsu (CN); **Fei Zhao**, Jiangsu (CN)
(73) Assignee: **Degrii Co., Ltd.**, Jiangsu (CN)
(**) Term: **15 Years**
(21) Appl. No.: **35/515,830**
(22) Filed: **Nov. 22, 2022**

(80) **Hague Agreement Data**

Int. Filing Date: **Nov. 22, 2022**
Int. Reg. No.: **DM/225454**
Int. Reg. Date: **Nov. 22, 2022**

(57) **CLAIM**

The ornamental design for a swimming pool cleaner with controller, as shown and described.

DESCRIPTION

1. Swimming pool cleaner with controller
1.1) front view;
1.2) back view;
1.3) left view;
1.4) right view;
1.5) top view;
1.6) bottom view;
1.7) Perspective view 1;
1.8) perspective view 2;
1.9) perspective view 3;
1.10) enlarged view of part of top panel of the controller in FIG. 1.5;
1.11) enlarged view of part of top panel of the controller in FIG. 1.7;
1.12) enlarged view of part of top panel of the controller in FIG. 1.8;
The broken lines represent portions that form no part of the claimed design.

(Continued)

The shade lines in the figures show contour, not surface ornamentation. The controller is shown in a larger scale relative to the swimming pool cleaner for clarity.

1 Claim, 11 Drawing Sheets
